UNITED STATES PATENT OFFICE.

GEORGE BEDFORD, OF TORONTO, ONTARIO, CANADA.

PLAYER-PIANO ACTION.

1,419,349.

Specification of Letters Patent. Patented June 13, 1922.

Application filed September 24, 1920. Serial No. 412,479.

To all whom it may concern:

Be it known that I, GEORGE BEDFORD, of the city of Toronto, in the county of York, Province of Ontario, Canada, a subject of the King of Great Britain, have invented certain new and useful Improvements in Player-Piano Actions, of which the following is a specification.

This invention relates particularly to the striking pneumatics of a player-piano and the valve mechanism through the medium of which the pneumatics are controlled by the passage of the music roll over the tracker bar, and my object is to devise a construction which will enable any individual valve mechanism to be quickly removed without disturbing other parts, and which permits of ready access to the under sides of the diaphragms of the valve mechanisms. Another object is to make the valve action as silent as possible.

I attain my objects by means of the constructions hereinafter described and illustrated in the accompanying drawings in which—

Fig. 1 is a vertical section of part of a player-piano mechanism illustrating my invention;

Fig. 2 a plan view of part of the air trunk, and

Fig. 3 a side elevation of a valve casing with the connecting diaphragm chamber.

In the drawings like numerals of reference indicate corresponding parts in the different figures.

1 is part of the frame of the action supporting the horizontal air trunk 2. This air trunk has a series of recesses 3 formed therein, one for each valve mechanism. Se- 40 cured to the air trunk below each recess 3 is a pneumatic 4, which actuates one of the hammers of the piano action (not shown). I show the pneumatic as connected with a striker wire 5 connected with the lever 6 45 suitably fulcrumed on the frame. 7 is the valve casing, which is provided with the usual valve chamber 8 provided with the alined valve seats 9 and 10, the valve seat 9 communicating with the atmosphere and 50 the valve seat 10 with the air trunk 2. A valve 12 of ordinary construction controls the passages through these valve seats. The upper part of the valve stem passes loosely through a hole in a felt washer 13. This 55 felt washer therefore acts as a guide to the valve stem, while permitting the free pas-

sage of air. It also silences the air intake when the pneumatic opens, whereas rigid wood or metal bridges are often found to be slightly noisy.

The diaphragm chamber is preferably of L-shape, the leg of the L forming the tracker bar communication 14 communicating with the passage through the body of the valve casing with which the usual tube 15 leading to the tracker bar is connected. A block 16 of felt or other suitable material is preferably inserted between the end of the diaphragm chamber remote from the leg and the under side of the valve casing, thus 60 serving to strengthen the connection between the valve casing and the diaphragm chamber.

The diaphragm 17 is of ordinary construction and is engageable with the lower end 65 of the valve stem in the usual manner. A bleed 18 is formed between the diaphragm chamber and the interior of the air trunk. An opening is formed in the under side of the valve casing communicating with the 70 valve chamber 8, which opening, when the valve casing is in position, is in alinement with the air duct 19 in the solid material of the air trunk, which air duct communicates with the interior of the pneumatic. 75 The valve casing is detachably secured in position, the preferred construction for that purpose being substantially as follows. A block or rib 20 is formed on or secured to the upper side of the air trunk, which block 80 has a series of recesses 21 formed therein one for each valve casing. Each valve casing has a pin 22 inserted in its end, which pin is adapted to engage in the recess 21. The reverse arrangement is, of course an 85 alternative.

The opposite end of each valve casing is releasably held down by means of a latch 23 pivoted either on the valve casing or the air trunk and engaging a pin 24. Prefer- 90 ably an alining pin 25 is inserted in the air trunk adapted to enter a hole formed in the under side of the valve casing.

As the mode of operation of a valve of the type shown is well known in the art, 105 a detailed description is not necessary. It will be noted, however, from the description and from the drawings that each individual valve casing with its attached diaphragm chamber is easily and quickly removed without disturbing any part of the mechanism other than the communication with the

tracker bar. Repairs and renewals are thus made with a minimum of trouble.

What I claim as my invention is:—

1. In a player-piano action, the combination of an air trunk having a recess in one side; a pneumatic connected to the air trunk; a valve casing having a diaphragm chamber connected therewith and detachably secured to the air trunk with the diaphragm chamber received within the recess, said valve casing and diaphragm chamber being removable as a unit; and an air duct leading from the pneumatic, the valve casing having a passage leading from the valve chamber adapted to register with said air duct when the valve casing is in place.
2. A player-piano action constructed as set forth in claim 1 provided with a bleed in the wall of the diaphragm chamber leading into the air trunk.
3. In a player-piano action, the combination of an air trunk having a recess in one side and an air duct leading from the said side through to the opposite side; a pneumatic connected to the air trunk and communicating with the air duct at the least mentioned side of the air trunk; a valve casing having a diaphragm chamber connected therewith and detachably secured to the air trunk with the diaphragm chamber received

within the recess and the valve chamber of the casing in communication with the air duct aforesaid.

4. A player-piano action constructed as set forth in claim 1 in which the means for detachably connecting the valve casing to the air trunk comprises a block on the air trunk having a recess in its side facing the valve casing; a pin on the valve casing adapted to enter said hole; and a latch detachably holding the opposite end of the valve casing to the air trunk. 40

5. A player-piano action constructed as set forth in claim 1 in which the diaphragm chamber is of L-shape, the leg of the L 45 forming the tracker bar communication.

6. In a player-piano action, a valve casing having a valve chamber therein provided with aligned valve seats facing one another; a valve adapted to engage either seat and provided with a fixed stem; and a felt washer secured to the casing having an aperture therein through which the valve stem passes sufficiently small to guide the valve stem and maintain the valve in alignment with the seats while permitting a sufficiently free passage of air. 50 55

Signed at Toronto, Canada, this 11th day of September, 1920.

GEORGE BEDFORD.
